BRACELET CHAIN.

Application filed March 21, 1924. Serial No. 700,748.

This invention relates to bracelet chain construction.

One of the objects of this invention is to provide a bracelet chain of durable and rugged construction and well adapted to meet the conditions of hard, practical use. Another object is to provide a construction of the above-mentioned nature which will be of efficient and thoroughly reliable action when in use. This invention aims also to provide a bracelet chain which will be not only of simple and thoroughly practical construction, thus lending itself to rapid and inexpensive manufacture, but also of neat and attractive appearance, of great comfort when in use, and of great durability. Other objects will be in part obvious or in part pointed out hereinafter.

The invention accordingly consists in the features of construction, combinations of elements, arrangements of parts, and in the several steps and relation and order of each of the same to one or more of the others, all as will be illustratively described herein, and the scope of the application of which will be indicated in the following claims.

In the accompanying drawing, in which is shown one of various possible embodiments of the several mechanical features of this invention,

Figure 1 is a top plan view of a portion of a bracelet chain, certain parts being omitted in order to show the construction more clearly.

Figure 2 is a bottom plan view of the construction shown in Figure 1.

Figure 3 is a side view as seen from the front of Figure 1.

Figure 4 is a central longitudinal cross-section taken substantially along the line 4-4 of Figure 1.

Figure 5 is a central transverse sectional view taken substantially along the line 5-5 of Figure 1.

Figure 6 is a side view of what may be termed a block-link, showing this block-link in one stage of its manufacture.

Figure 7 is a sectional view taken sub-

stantially along the line 7-7 of Figure 6, and

Figure 8 is a plan view of a chain-link in one stage of its manufacture.

Similar reference characters refer to similar parts throughout the several views of the drawing.

As conducive to a clearer understanding of this invention, it may here be pointed out that a dominant aim of this invention is to provide a bracelet chain, the exposed sections or links thereof having a solid or block-like appearance. These exposed block-like members may be ornamented in any desired manner to give the bracelet chain the desired attractive appearance. Bracelet chains in general are of relatively minute construction and hence are none too well adapted to meet even the ordinary conditions of practical use. They must be not only sufficiently strong to perform reliably their normal or intended functions but also sufficiently rugged to withstand abnormal strains inadvertently imposed upon them. The relatively diminutive character of such bracelet chains thus oftentimes precludes the avoiding of such disadvantages simultaneously with the attainment of inexpensive or economical manufacture. Accordingly, this invention aims to combine in a thoroughly practical way the advantages of rapid and inexpensive manufacture with the advantages of strength, ruggedness and durability of construction.

Referring now to the drawing in detail, and more particularly to Figures 1, 2 and 3, there is shown a series of members 10 which will hereinafter be termed chain-links. Each chain-link 10 is preferably made of sheet metal and is preliminarily stamped or cut in the shape or form shown in Figure 8. The sheet metal out of which the chain-link 10 is made is a base metal and the character of the latter may be so chosen as to give to the chain-links the desired strength. Preferably the chain-link 10 is made of brass.

Referring now more specifically to Figure

8, in which is shown the stamping out of which each chain-link 10 is made, it will be seen that the sheet metal is in general of a rectangular shape, has an opening 10^a, also 5 of rectangular shape, stamped or cut out at one end of the sheet metal, and at the opposite end of the strip of sheet metal, the latter is cut away at opposite lateral portions thereof, as at 10^b and 10^c. There is 10 thus formed at the one end of the sheet metal strip, or at the right-hand end thereof as viewed in Figure 8, a substantially T-shaped portion 10^d. The strip of sheet metal having thus preliminarily been stamped or cut 15 to give it substantially the form shown in Figure 8, the opposite end portions are thereupon bent over to form what may be termed connecting loops. The left-hand portion of the member 10, referring still to Figure 8, 20 is bent over a suitable mandrel, the axis about which this left-hand end portion is bent being indicated generally by the line A—A of Figure 8. Similarly, the right-hand portion of the sheet metal strip is bent 25 over a suitable mandrel and, like the left-hand portion, is bent substantially backwardly upon itself. The axis about which the T-shaped right-hand end portion of the sheet metal strip, referring still to Figure 30 8, is bent is indicated generally by the line B—B.

In Figures 3 and 4, the completely bent-over end portions are clearly indicated. The member 10^d will be seen to form a connecting loop, indicated also at 10^d in these figures, whereas the bent-over left-hand portion will be seen to have formed two spaced connecting loops 10^e and 10^f, more clearly shown in Figure 1 of the drawing. Bearing 40 in mind that these end portions of the sheet metal stamping have been bent over a cylindrical mandrel, it will be noted that each of the connecting loops 10^a, 10^e and 10^f thus formed is thus provided with an interior bearing surface which is substantially cylindrical throughout the extent of each loop. The connecting loop 10^d of one link is thereupon fitted between the spaced connecting loops 10^e and 10^f of a succeeding loop, thus 45 placing in alignment the cylindrical bearing surfaces upon the interior of these connecting loops. A stud 11, of cylindrical shape, is thereupon passed through the aligned loops 10^e, 10^d and 10^f, thus pivotally connecting one chain link to the next. At this 55 point it might be noted that the connection thus provided between adjacent links is of the greatest possible degree of flexibility, inasmuch as the parts, pivoting one from the other, are provided with not only cylindrical pivoting studs 11 but also with cylindrical bearing surfaces with which the studs 11 may efficiently coact. The mandrels about 60 which the end portions of the chain-link

blank are bent are preferably of substantially 65 the same diameter as are the pivoting studs 11. If desired, the end portions of the chain-link blank may be given a preliminary bend, and thereupon a final bend over the connecting studs 11 themselves. 70

Turning now again to Figure 8 of the drawing, it will be noted that the extreme end portions of the chain-link blank comprise what may be termed a cross-bar 10^g at one end thereof and a cross-bar 10^h at the 75 other end thereof. As the end portions of the chain-link blank are finally bent backwardly upon the main or central portion of the chain-link blank, these cross-bars 10^g and 10^h will assume the positions shown in 80 Figure 4, it being noted that the end portions are bent over upon the same side of the main or central portion of the chain-link blank.

The block-links are preferably also of 85 sheet metal and desirably are made of a suitable base metal, the exterior surface of which is preferably filled or plated with a suitable precious metal. Thus, for example, the exterior portions of the sheet metal 90 block-link may be gold-plated or gold-filled. These block-links comprise preferably a substantially rectangular-shaped plate member generally indicated at 12, the length of 95 which in the direction in which the chain is to extend is substantially equivalent to the distance between the axes of two successive connecting studs 11. This will be clear from a consideration of Figure 4. The plate member 12 is provided with two depending side walls 12^a and 12^b (see Figure 7, integrally 100 formed therewith. The side walls 12^a and 12^b are spaced apart from one another sufficiently so as to snugly receive therebetween one of the chain-links 10. Thus, for example, the chain having been completed by 105 connecting the chain-links 10 together through the connecting studs 11, a block-link 12 is superimposed upon each chain-link 10, the latter being snugly received between the spaced side walls 12^a and 12^b of 110 the sheet metal block-link 12.

The end edges of the side walls 12^a and 12^b, as viewed in both Figures 3 and 6, are 115 extended downwardly in substantially parallel relation one to another and to such a distance that these parallel side edges terminate substantially at mid-point of the circular end face of the connecting studs 11. Thereupon the side edges are extended inwardly 120 toward one another as at 12^c (see Figure 6), whence the side walls 12^a and 12^b are then further extended to provide the end flanges 12^a and 12^b. The latter, as is clearly shown in Figure 6, have substantially parallel end edges, the distance between which is substantially equivalent to the length of the plane portion of a chain-link 10. Prefer- 125

ably the flanged portions 12^a and 12^b are under-cut, as is clearly shown in Figure 7, so as to make these end flanges 12^b and 12^a of somewhat lesser thickness than the thickness of the sheet metal out of which the block-link is formed. By making these end flanges 12^a and 12^b of reduced thickness, a more compact construction is achieved, it being noted, as shown also in Figures 3 and 4, that these end flanges of reduced thickness, when bent inwardly upon the chain-link, substantially snugly fit between the spaced connecting loops 10^c of successive links 10 and thus are made to lie substantially within the outer plane passed through the outermost points of these connecting loops. Moreover, a more uniform and continuous surface of contact to the wrist, for example, is thus presented. In Figure 7 also is indicated the covering 12^c of precious metal, either filled or plated, upon the exterior surface of the block-link 12.

The block-link 12, having been superimposed upon a chain-link 10, the latter being received between the side walls 12^a and 12^b, the flanges 12^a and 12^b are thereupon bent inwardly toward one another and into substantially the position shown in Figure 5. It will be noted that the block-link 12 is superimposed upon a chain-link 10 in such manner that the end cross-bars 10^e and 10^f of the chain-link will be adjacent the main plate member 12 of the block-link, as is shown in Figure 4. The end flanges 12^a and 12^b, upon being bent inwardly as shown in Figure 5, securely clamp the block link 12 to the chainlink 10, and at the same time securely lock the end cross-bars 10^e and 10^f in position and against any possibility of being pulled out or distorted. The clamping flanges 12^a and 12^b, having a length in the direction in which the chain extends which is substantially equivalent to the plane portion or surface of the underside of a chain-link 10, substantially mate therewith and fit between successive loops of the chain-links. The block-link 12 is thus prevented from partaking of any movement relative to the chain-link 10 in the direction of the length of the chain.

Turning now to Figure 3, it will be seen that the side walls 12^a and 12^b of the block-link 12 overlap the exposed ends of the pivoting studs 11, and thus prevent the dropping out of the connecting studs 11. The latter, it will further be noted, need not be headed over, soldered, or otherwise secured with respect to the chain-links 10. It will also be noted that the parallel end edges of the side walls 12^a and 12^b terminate substantially at the axes of the pivoting studs 11, whence, as hereinabove described, they extend inwardly toward each other as at 12^c (Figure 3 and Figure 6). The flexing of the brace-

let chain is thus unhampered and may freely take place, it being further pointed out that the connecting studs 11 with the associated connecting loops of the chain-links provide most efficient cylindrical bearing surfaces for permitting ready flexing of the bracelet chain to take place. Moreover, the chain-link construction and the manner of connecting the chain-links together, in providing in effect the most practical form of hinged construction, insure the maintenance of the block-links in longitudinal alignment by avoiding lateral or angular displacement or play between adjacent links.

The bent-over side flanges 12^a and 12^b (Figure 5), aside from effectively locking the various parts in assembled relation, moreover, where the exterior surface of the block-link 12 is filled or plated with a precious metal, as is shown in Figures 5 and 7, provide a precious metal under-surface for exposure to or contact with the skin, the base metal portion of these flanges providing sufficient strength for effectively clamping and locking the parts together mechanically.

It will thus be seen that there has been provided in this invention a bracelet chain construction and method of making the same in which the several objects hereinbefore noted as well as many thoroughly practical advantages are achieved. It may first be noted that the method herein provided may be inexpensively, rapidly and economically carried on. The individual parts are of simple construction, and thus lend themselves readily to inexpensive manufacture; the parts moreover may be rapidly but effectively assembled, it being pointed out that such tedious and expensive operations as soldering for example may be effectively avoided. Moreover, the bracelet chain is of exceedingly rugged construction, it being noted that the construction is sufficiently rugged to meet not only the conditions of ordinary use but also conditions of abnormal use not infrequently imposed upon devices of this character. The construction is well adapted to meet unusual strains imposed upon it, inasmuch as the effective connecting portions thereof are securely locked in position and against distortion. Moreover it will be seen that all of these thoroughly practical advantages are achieved without detracting from the feasibility of attaining both rapid and inexpensive manufacture.

As many possible embodiments may be made of the mechanical features of the above invention and as the art herein described might be varied in various parts, all without departing from the scope of the invention, it is to be understood that all matter herein set forth or shown in the accompany-

ing drawing is to be interpreted as illustrative and not in a limiting sense.

I claim as my invention:

1. In construction for bracelet chains and the like, in combination, a chain having sheet metal links, an end of each of which is bent over substantially upon itself to form a connecting loop, a plate-like member mounted upon each link, and means rigidly 10 clamping together the bent-over end of a sheet metal link member and said plate-like member.
2. In construction for bracelet chains and the like, in combination, a chain having sheet metal links, an end of each of which is bent over upon itself to form a connecting loop, and a plate-like member for each link and having depending side walls between which a link of said chain is received, 15 the ends of said side walls being bent over to clamp rigidly a link therebetween and said plate member and to clamp said bent over ends of said links against unbending.
3. In construction for bracelet chains and the like, in combination, a chain having sheet metal links, an end of each of which is bent over upon itself to form a connecting loop, connecting studs passing through connecting loops of adjacent links, and a 20 plate member mounted upon each link, said plate member having depending means adapted to overlap the ends of said studs to hold them in position.
4. In construction for bracelet chains and the like, in combination, a chain having sheet metal links, an end of each of which is bent over upon itself to form a connecting loop, connecting studs passing through connecting loops of adjacent links, and a plate member for each link and having depending side walls extending over the ends of the studs 25 to hold the latter in position, the extreme end portions of said side walls being bent inwardly upon a link to hold said plate member upon said link.
5. In construction for bracelet chains and the like, in combination, a chain comprising a plurality of links each having two spaced connecting loops at one end and a centrally 30 positioned connecting loop at the other end, said last-mentioned loop being arranged to be received between the two spaced loops of an adjacent link, a connecting stud passed through aligned connecting loops of adjacent links, a plate member for each link and having a length in the direction of the length 35 of the chain substantially equivalent to the distance between the axes of adjacent studs, and means for securing said plate member to a link.
6. In construction for bracelet chains and the like, in combination, a chain comprising a plurality of links each having two spaced connecting loops at one end and a centrally 40 positioned connecting loop at the other end,
7. In construction for bracelet chains and the like, in combination, a chain comprising a plurality of links each having two spaced connecting loops at one end and a centrally positioned connecting loop at the other end, 45 said last-mentioned loop being arranged to be received between the two spaced loops of an adjacent link, a connecting stud passed through aligned connecting loops of adjacent links, and a plate member secured to each link and having depending portions adapted to overlap the ends of said connecting studs to hold the latter in position.
8. In construction for bracelet chains and the like, in combination, a chain comprising a plurality of links each having two spaced connecting loops at one end and a centrally positioned connecting loop at the other end, 50 said last-mentioned loop being arranged to be received between the two spaced loops of an adjacent link, a connecting stud passed through aligned connecting loops of adjacent links, and a plate member for each link, having a length substantially equivalent to the distance between the axes of adjacent studs, said plate member having depending side flanges between which a link is received and said flanges being bent over upon the link to hold said plate member in assembled relation with respect thereto.
9. In construction for bracelet chains and the like, in combination, a chain having a plurality of sheet metal links each provided with two spaced connecting loops at one end and a centrally positioned connecting loop at the other end thereof, each of said loops being formed by bending over an end portion of the sheet metal of the link, connecting studs passed through aligned connecting loops of adjacent links, a plate member for each link, having a length substantially equivalent to the distance between the axes of adjacent connecting studs, and means for simultaneously securing said plate member upon a link and holding said bent-over loop-forming portions in position.
10. In construction for bracelet chains and the like, in combination, a chain having a plurality of sheet metal links each provided with two spaced connecting loops at one end and a centrally positioned connecting loop at the other end thereof, each of said loops being formed by bending over an end portion of the sheet metal of the link, connecting studs passed through aligned connecting loops of adjacent links, a plate member for each link, having a length substantially equivalent to the distance between the axes of adjacent connecting studs, and depending side flanges on said plate member and between which a link is received, said side flanges being bent over to hold said plate member in position and to lock said bent-over loop-forming portions of the link against unbending.
11. In construction for bracelet chains and the like, in combination, a chain having a plurality of sheet metal links each provided with two spaced connecting loops at one end and a centrally positioned connecting loop at the other end,

at the other end thereof, each of said loops being formed by bending over an end portion of the sheet metal of the link, connecting studs passed through aligned connecting loops of adjacent links, a plate member for each link, having a length substantially equivalent to the distance between the axes of adjacent connecting studs, and depending side flanges on said plate member adapted to overlap the ends of said connecting

studs to hold the latter in position within said connecting loops, said side flanges being bent over to hold said plate member in position and to lock said bent-over loop-forming portions of the link against unbending. ¹⁵

In testimony whereof, I have signed my name to this specification this fourteenth day of March, A. D. 1924.

AXEL PERSON.
